UNITED STATES PATENT OFFICE.

WINFIELD W. MULLEN AND FRANCIS M. MULLEN, OF BUNKER HILL,
INDIANA.

CULTIVATOR.

SPECIFICATION forming part of Letters Patent No. 427,888, dated May 13, 1890.

Application filed October 12, 1889. Serial No. 326,863. (No model.)

To all whom it may concern:

Be it known that we, WINFIELD W. MULLEN and FRANCIS M. MULLEN, citizens of the United States, residing at Bunker Hill, in the county of Miami and State of Indiana, have invented certain new and useful Improvements in Cultivators, of which the following is a specification.

Our invention consists in certain improvements in the details of construction of cultivators by which a very convenient, complete, and comparatively inexpensive machine is provided, as will be hereinafter more fully set forth.

15 Referring to the accompanying drawings, which are made a part hereof, and on which similar letters of reference indicate similar parts, Figure 1 is a perspective view of a cultivator of our improved construction; Fig. 2, 20 a top or plan view of the same; Fig. 3, a detail sectional view, on an enlarged scale, on the dotted line 3' 3 in Fig. 2; and Fig. 4, a similar view showing a modified form.

In said drawings, the portions marked A 25 represent the main frame of the device; B, side wings hinged thereto, and C the cultivator-teeth.

The main frame A preferably consists of two side pieces connected at their front ends, 30 extending back at an angle, and secured together by a cross-bar near their rear ends, as shown. The side wings B are hinged one to each of said pieces by means of curved or semicircular irons B', attached thereto with their curved sides projecting therefrom, and provided with a series of perforations b, 35 through one of which and a hole in the end of each wing a pin b' extends. By means of the series of perforations said wings may be pivoted at any point desired, and a stop-pin b² is inserted behind the pivot, on the outside of the wing, to limit the outward movement thereof, which movement may thus be regulated as desired. A spring B² is secured between the main frame A and each wing, arranged to bear against the wings and force them outward, the tension of said springs being regulated by means of a bolt b³, which passes through an outwardly-curved end of 50 each behind the point where they rest against

the side pieces of the main frame, and by which said wing may be drawn down closely against said main frame, thus increasing the force with which its opposite end bears against the wing, as will be readily understood.

55

The teeth C are "spring-teeth," formed of a piece of flat spring metal bent substantially as shown, and are secured to the frame by means of a clamp consisting of a bolt C', provided with an elongated slotted head c', which rests in a recess c² in the top of a washer or clamping-jaw C², which rests against the frame, and through which said bolt passes. With the form of tooth shown this bolt is inserted from and secures the teeth on the top of the frame; but, as will be readily understood, the tooth could be of such a form that the bolt might be inserted from the under side of the frame, and such a construction is shown in Fig. 4. By the form of the clamping arrangement the tooth is allowed to be adjusted very readily, as by simply loosening the nut on the end of the bolt the tooth may be turned to present its point to the soil at any angle desired or to any depth, the part of the tooth which passes through the head of the bolt being curved, and the sliding of it to different positions therein operating, as will be readily understood, to lift the point of the tooth or lower it, as may be desired. It is also convenient for the purpose of adjusting the tooth sidewise to the position desired, as the bolt may be turned to any angle on the frame. The form of the clamp is such as will hold the tooth very secure and rigid to position, but at the same time permit its ready and easy adjustment, as just described. By this arrangement a cultivator is provided which is very complete and convenient to operate by reason of the spring-mounted wings and the mechanism by which they are adjusted to the width desired, and the device for securing the spring-tooth in place, by which any form of spring-tooth may be secured in a manner which permits its easy adjustment.

95

Having thus fully described our said invention, what we claim as new, and desire to secure by Letters Patent, is—

The combination, in a cultivator, of the main frame A, the curved hinge parts B', with

100

a series of perforations therein, secured to the
sides of said frame, the wings B, pivoted to
said parts B', the adjustable stop-pins b², the
springs B², interposed between said frame and
said wings, the spring-teeth C, and the slotted
head-bolt C' and clip C² for securing said
teeth in place, substantially as set forth.

In witness whereof we have hereunto set

our hands and seals, at Indianapolis, Indiana,
this 27th day of September, A. D. 1889.

WINFIELD W. MULLEN. [L. S.]
FRANCIS M. MULLEN. [L. S.]
